UNITED STATES PATENT OFFICE.

HARRY E. STRUNK, OF ONTARIO, CALIFORNIA, ASSIGNOR, BY MESNE ASSIGNMENTS, TO MAJESTIC ELECTRIC DEVELOPMENT COMPANY, A CORPORATION OF CALIFORNIA.

HEATER.

Application filed August 13, 1917. Serial No. 185,893.

To all whom it may concern:

Be it known that I, HARRY E. STRUNK, a citizen of the United States, residing at Ontario, in the county of San Bernardino and State of California, have invented a new and useful Heater, of which the following is a specification.

My invention relates to portable electric heaters in which the heat from the heating element is directed and concentrated in some direction. As such heaters, in order to be of commercial value, must be comparatively light, there is considerable danger of such heaters being upset, and if upset to such a position as to direct the heat of the element against an inflammable floor material or floor covering, there is great danger of scorching or burning the floor material or covering.

An object of my invention is to provide a heater which is so shaped, and in which the weight is so distributed, that the heater when upset will automatically turn into a safe position.

In the drawings, which are for illustrative purposes only:

Fig. 1 is a front elevation of the heater, a portion of the guard being broken away, and a portion of the heating unit being shown in section.

Fig. 2 is a side elevation, partly in section, showing the method of adjusting the heater.

Fig. 3 is a view, on an enlarged scale, showing the method of securing the guard to the reflector.

Fig. 4 is a sectional plan view of a portion of the heater, showing the method of supporting the heating unit.

Fig. 5 is a view of the heater, seen from the bottom, as it would appear were it held in position by the hand, as shown in that figure. The heater in this position is in an unstable position and will immediately roll into the position shown in Fig. 6 upon removing the hand.

Fig. 6 is a view of the heater lying on its side in the stable position which it will assume if it be tipped over.

The heater shown in these drawings consists of a reflector 11 supported on a standard 12 and provided with a heating element 13 and a guard 14. The reflector 11 is preferably of parabolic shape and is provided with a handle 20 by which the heater may be transported from place to place. It is

also provided with a socket 21 into which a standard attachment plug 22 may be inserted, this attachment lug 22 being provided with a duplex flexible cord 23 through which electricity is supplied to the heater. Located inside the socket 21 are terminals 24 which pass through the reflector 11, being insulated therefrom.

Secured to the reflector 11 is a pair of standards 25, preferably formed of sheet metal, which are bent as shown in Fig. 4 and which are provided with small ears 26, shown in that figure. The standards 25 are preferably formed of sheet metal and have considerable spring so that they are held pressed inside an insulating cylinder 27 of the heating element 13, fine wire 28, preferably in coils, being wound around the outside of the cylinder 27 and having terminal wires 29 which pass back and connect to the terminals 24. The cylinder 27 can be readily removed from the standards 25 by springing them out into the position shown at A in Fig. 4.

In operation, the wire 28 is raised to a glowing temperature, and it is necessary to protect it from accidental contact with fabrics. This is accomplished by means of the guard 14 which consists of a series of wires 30 which are connected to a common central point 31, and which are connected at their other end to a ring 32. This ring is provided with small hooks 33, as best shown in Fig. 3, which pass through holes 34 formed in the reflector 11 at the top and bottom thereof. The guard 14 is readily removed by pressing downwardly on the ring 32 adjacent to the upper hole 34, thus springing the hook 33 downward and allowing it to be withdrawn through the hole 34.

The reflector 11 is provided with a pair of ears 35 which are pivoted on a screw 36 which passes through a cap 37 of the standard 12. This standard 12 has a base 38 which may be of any desired ornamental form. Were the guard 14 to be made flat in form, or were it to be dispensed with, the reflector if overturned might fall in such a position that the heat rays from the reflector 11 would be directed downwardly against the carpet. For the purpose of preventing this I prefer to give the guard 14 a curved shape, as shown in the drawings, and in addition I place in the base 38 a heavy weight 39, the center of

gravity 40 of this weight being displaced by an angle M of approximately 45° from the central plane N—N of the reflector 11. By placing the center of gravity 40 off center, as best shown in Fig. 5, the heater when placed in the position shown in Fig. 5 will tend to rotate in the direction of the arrow 41, assuming the position shown in Fig. 6. It will also tend to assume the position shown in Fig. 6 if placed in any position other than one which would make it tend to assume position shown in Figs. 1 and 2.

The method of operation of the invention is as follows:

15 The heating element being supplied with current through the wires 23, is brought up to a glowing heat, and this heat is directed outwardly from the heater in approximately parallel rays by the reflector 11. The direction of these rays of heat can be readily changed into a horizontal plane by adjusting the position of the whole heater around its vertical axis. For the purpose of changing the direction of the heat up or down, the 20 adjustment about the screw 36 is provided, the heater being readily adjustable from the position shown in full lines in Fig. 2 to the position shown in dotted lines in that figure. By this means the heat can be directed to 25 approximately any position desired.

I have found that by the use of a heater of this kind it is possible for a person to be quite comfortable even in a very cold room, so that it is unnecessary to provide, in electric heating, for heating the entire space 30 about the person. In other words, I pro-

vide for heating the body of the person desiring the warmth and not the surrounding air.

I claim my invention:—

1. In an electric heater, a reflector; and an outwardly curved guard over the front of said reflector, the weight of said heater being so distributed that said heater tends to roll into a position with the guard upward when 45 over turned.

2. In an electric heater a heating element; a reflector for said heating element; a stand; and the mass of said heater being so distributed that said heater is in unstable equilibrium in any position which would reflect the heat downward.

3. In an electric heater, a heating element; a reflector for said heating element; a stand supporting said element and reflector; and a 50 weight so located as to throw said reflector between said element and any flat surface upon which said heater may be overturned.

4. A combination as in claim 3 in which said weight is placed in the base of said 55 stand.

5. In a portable electric heater, a heating element and a standard and reflector for directing the heat from said element, the weight of said parts being so distributed that 60 if said heater is left in such a position as to direct the heat downward, it will automatically move from such position.

In testimony whereof, I have hereunto set my hand at Ontario, California, this 3rd day 70 of August, 1917.

HARRY E. STRUNK.
